E. B. PETERS

DIVIDER BOARD FOR MOWERS

Filed Dec. 1, 1927

UNITED STATES PATENT OFFICE.

EMIL B. PETERS, OF GEORGETOWN, KENTUCKY.

DIVIDER BOARD FOR MOWERS.

Application filed December 1, 1927. Serial No. 237,064.

This invention relates to divider boards for mowers and more particularly to a divider board pivotally mounted, so that in event of its engagement with an obstruction 5 during backing of the mower, it may yield inwardly and thus prevent breakage thereof.

An important object of the invention is to provide in a construction of this character a spring return hinged leaf upon which the 10 divider board is mounted and which is, in turn, mounted upon the outer shoe of the reaper, the return mechanism for the leaf being of such character that it may be entirely concealed within the structure of the divider 15 board under normal operating conditions and accordingly may not be damaged or interfered with in its operation by contact with materials through which the board is moving.

20 A further object of the invention is to provide a construction such that when the board is flexed or moved about its pivot, the spring connection for returning the board to its normal position is shifted in such a manner that it is well spaced from the pivotal 25 mounting of the board and accordingly the spring may exercise its tension to the best advantage.

These and other objects I attain by the 30 construction shown in the accompanying drawings, wherein for the purpose of illustration is shown a preferred embodiment of my invention and wherein:—

Figure 1 is a side elevation of a divider 35 board constructed in accordance with my invention;

Figure 2 is a longitudinal sectional view therethrough, the board being illustrated in its normal position in solid lines and in its 40 yielding position in dotted lines;

Figure 3 is a fragmentary side elevation of the inner face of the board and the attached plates.

Referring now more particularly to the 45 drawings, the numeral 10 generally designates the outer shoe of a mower to which, in accordance with my invention, I attach through a bolt 11 a plate 12 to which a second plate 13 is hinged at 14. Each of the 50 plates 12 and 13 have at adjacent edges thereof scrolls forming eyes for the passage of the hinge pin and the plate 13 hereinafter re-

ferred to as the rear plate has a tongue 16 between its scrolls which extends forwardly and outwardly from the forward edge of the plate and is provided with an enlarged head 17 at its forward end. This head is preferably produced by rolling the plate, but may be produced in any desirable manner.

Securely bolted to the plate 13 is the divider board 18, the forward end of which has a longitudinal slot 19 opening its forward end and into which the tongue 16 and its head 17 extend. The bolt 11 extends through the plate 12 for a considerable distance and passes through the forward end of a plate, generally designated at 20. Outwardly of this plate, this bolt has mounted thereon a spring 21, the inner end of which abuts the plate 20 and the outer end of which seats against a nut 22. The forward end of the plate 20 is inturned, as indicated at 23, to provide a pivot upon which the plate may oscillate. Rearwardly of the bolt, the plate 20 extends to the opposite side of the edge 17 from the plate 12. Rearwardly of the head 17, the plate 20 is bent inwardly toward the general plane of the plate 12 and the rear end thereof has an angular flange 25. The flange 25 and the adjacent portion of the plate are provided with a central slot 26 through which is apertured a stem 27 having a head 28 seating upon the flange at its forward end and an eye 29 at its rear end, to which is connected one end of a spiral spring 30, the opposite end of which is connected to an eye 31 mounted at the rear end wall of the slot 19 of the divider board.

Under normal operating conditions, the plates 12 and 13 are in longitudinal alignment and the forward end of the arms formed by the slot of the divider board bear against the outer face of the plate 12 and are held thereagainst by the tension of the spring 30 and further by the thrust applied to the board of cut material bearing thereagainst which it is the function of the board to shift to one side to provide a clear division between the cut and uncut material. If, in backing the mower, the board, which engages the ground, comes into contact with an obstruction, which tends to force the board inwardly, the plate 13 swings about the pivot pin 15, permitting the board to assume an

angle to the plate 12. In this operation, the head 17 is swung outwardly from the plate 12, forcing before it the spring supporting plate 20, with the result that the rear end of the spring supporting plate moves transversely and the head 28 is further spaced from the pivot 15 than it is normally. By this movement, the tension of the spring 30 is increased and the angular pull thereof likewise increased, with the result that this spring will immediately, upon release of the pressure holding the board in its abnormal position, move the board back to its normal position in alignment with the plate 12. In doing this, the spring 21, which is a relatively heavy spring, also acts to assist in the return of the board, for the tension of this spring being applied to the plate 21 rearwardly of the pivot thereof, applies pressure to the head 17, tending to rotate the plate 13 and accordingly the board to which it is attached. In the normal position of the parts, the head 17 and plate 20 together with the spring 30 and the connections between the plate 20 and the spring are concealed within the slot of the board and accordingly held from access to materials being cut by the mower.

As the construction hereinbefore set forth is capable of a certain range of change and modification without materially departing from the spirit of the invention, I do not limit myself to such specific structure except as hereinafter claimed.

35 I claim:—

1. In combination with a mower shoe, a plate secured thereto, a second plate pivotally connected with the first named plate, a divider board bolted to said second plate adjacent its forward end, spring means connecting the divider board and the board plate normally maintaining the forward end of the divider board in engagement with the outer face of the first named plate and means operated by the angular displacement of the plates for shifting the spring connection between the first named plate and the divider board to maintain the same in spaced relation to the pivotal connection between the plates.

50 2. In combination with a mower shoe, a plate secured thereto, a second plate pivotally connected with the rear edge of the first named plate, a divider board bolted to the outer face of the second plate adjacent to but spaced from its forward end, the forward end of the divider board engaging the first named plate to limit rotation of the plates in one direction, a further plate having pivotal engagement with the forward plate at its forward end and spring-connected with the divider board at its rear end and an extension upon the forward edge of the second plate lying at the outer face of the first named plate when the plates are aligned with one another and forcing the rear end of the last named

plate outwardly from the pivotal connection as the first and second plates assume an angle to one another.

3. In combination with a mower shoe, a plate secured thereto, a second plate pivotally connected with the rear edge of the first named plate, a divider board bolted to the outer face of the second plate adjacent to but spaced from its forward end, the forward end of the divider board engaging the first named plate to limit rotation of the plates in one direction, a further plate having pivotal engagement with the forward plate at its forward end and spring-connected with the divider board at its rear end, an extension upon the forward edge of the second plate lying at the outer face of the first named plate when the plates are aligned with one another and forcing the rear end of the last named plate outwardly from the pivotal connection as the first and second plates assume an angle to one another, and a spring engaging the last named plate rearwardly of the point of pivotal engagement thereof with the first named plate and urging the last named plate toward the pivotal connection.

4. In combination with a mower shoe, a plate secured thereto, a second plate pivotally connected with the rear edge of the first named plate, a divider board bolted to the outer face of the second plate adjacent to but spaced from its forward end, the forward end of the divider board engaging the first named plate to limit rotation of the plates in one direction, a further plate having pivotal engagement with the forward plate at its forward end and spring-connected with the divider board at its rear end and an extension upon the forward edge of the second plate lying at the outer face of the first named plate when the plates are aligned with one another and forcing the rear end of the last named plate outwardly from the pivotal connection as the first and second plates assume an angle to one another, the forward end of the divider board having a longitudinally extending slot within which said extension of the second named plate and the last named plate are disposed when the first and second plates are aligned.

5. In combination with a mower shoe, a plate secured thereto, a second plate pivotally connected with the rear edge of the first named plate, a divider board bolted to the outer face of the second plate adjacent to but spaced from its forward end, the forward end of the divider board engaging the first named plate to limit rotation of the plates in one direction, a further plate having pivotal engagement with the forward plate at its forward end and spring-connected with the divider board at its rear end, an extension upon the forward edge of the second plate lying at the outer face of the first named plate when the plates are aligned with one another and

forcing the rear end of the last named plate outwardly from the pivotal connection as the first and second plates assume an angle to one another, and a spring engaging the last named plate rearwardly of the point of pivotal engagement thereof with the first named plate and urging the last named plate toward the pivotal connection, the forward end of the di-

vider board having a longitudinally extending slot within which said extension of the second named plate and the last named plate are disposed when the first and second plates are aligned.

In testimony whereof I hereunto affix my signature.

EMIL B. PETERS.
